UNITED STATES PATENT OFFICE.

HENRY RICHARDSON, OF CHICAGO, ILLINOIS.

CORNER LOCK FOR BEDSTEADS.

Application filed December 5, 1921. Serial No. 519,870.

To all whom it may concern:

Be it known that I, HENRY RICHARDSON, a subject of the King of Great Britain, residing at Chicago, in the county of Cook 5 and State of Illinois, have invented certain new and useful Improvements in Corner Locks for Bedsteads, of which the following is a specification.

This invention pertains to improvements 10 in what are commonly known as corner locks for bedsteads, including the instrumentalities by which the side or end rails, or both, of a bedstead frame are separably united to the corner posts of the 15 latter.

One object of the present invention is to provide an improved corner post bracket preferably of a generally box-like form to receive the end of the side rail or an attachment thereto, which bracket is preferably made of sheet-metal and is characterized by lightness, strength, simplicity and durability for cooperation with side rail fastening and locking devices. Another important object of the invention is to provide a simple means for strongly and rigidly locking the side or end rails or both to the corner post bracket and which will securely hold the side rail in the bracket 30 under the weight carried by the bed frame and against longitudinal pulling strains. A still further object of the invention is to provide an improved construction of corner bracket and locking means that will permit the side rails to be inverted so as 35 to support either a bed spring frame or slats.

Other objects and attendant advantages 40 of the invention will be apparent to persons skilled in the art as the same becomes better understood by reference to the following detailed description, taken in connection with the accompanying drawings, wherein I have illustrated several specific 45 forms or embodiments of the principle of the invention, and in which—

Fig. 1 is a plan view of a sheet-metal blank from which my improved corner bracket is formed; 50 Fig. 2 is a side elevation of my improved bracket shown applied to a corner post, and with the side and end rails secured thereto by my improved locking means;

Fig. 3 is a vertical section on the line 55 3—3 of Fig. 2;

Fig. 4 is a horizontal section on the line 4—4 of Fig. 3;

Fig. 5 is a fragmentary perspective view of the end portion of a side rail, that fits within the corner bracket; 60

Fig. 6 is a fragmentary perspective view of an end portion of an end rail that is attached to the corner bracket;

Fig. 7 is a perspective elevation of a keeper lug constituting an element of the 65 device for locking the side rail to the top plate of the bracket;

Figs. 8, 9 and 10 are views corresponding to Figs. 2, 3 and 4, respectively, showing a modification adapted for the inverting of the side rail, and also affording a lock for the latter on both sides of the bracket; 70

Fig. 11 is a view similar to Fig. 9 showing the side rail in horizontal inverted position; 75

Fig. 12 is a perspective view of an end portion of the side rail and an attachment or extension member secured thereto adapted for cooperation with the corner bracket 80 shown in Figs. 8 to 11.

Figs. 13, 14 and 15 are views corresponding to Figs. 2, 3 and 4, showing another modification;

Fig. 16 is a perspective view of the end portion of a side rail and an extension member secured thereto adapted for cooperation with the corner bracket shown in Figs. 13, 14 and 15; 85

Fig. 17 is a detail perspective view of a 90 modified form of keeper lug;

Figs. 18, 19 and 20 are views corresponding to Figs. 2, 3 and 4, showing another modification adapted to permit the side rail to be engaged with and locked to the corner 95 bracket in either upright or inverted position;

Fig. 21 is a perspective view of an end portion of the side rail and an attachment member secured thereto and designed to co-operate with the corner bracket of Figs. 18, 19 and 20 and its locking devices. 100

The present invention is of that type which preferably employs a box bracket on the corner post and a side rail having an end, or end attachment thereof, entered in said bracket; and the novel features relate mainly to improved means for removably securing the side rail, or rail attachment, in the bracket, said securing means being de- 105

signed to accomplish four principal objects, namely, to strongly support the side rail against the weight carried by the bed frame, to prevent any possibility of the rail pulling 5 out of the socket of the bracket, to maintain a rigid rectangular relation of the side rail and the corner post of the bed frame and prevent any tipping or canting of the corner post either under a load on the bed frame 10 or by pulling or pushing the latter over the floor, it being well known that the latter operation involves a severe bending strain on the corner brackets and the bed rail fastening means and to provide an improved 15 construction permitting the side rail to be used in either upright or inverted position. In the accomplishment of these objects, as disclosed by the drawings and as hereinafter described, the bracket and side rail are held 20 against relative longitudinal and relative lateral movement by means including a vertically disposed rail locking element, herein shown as a lug projecting from one of the said parts, embraced by a co-operating rail 25 locking element on the other of said parts, said means acting jointly with rail locking devices on a side plate of the bracket and a vertical limb of the side rail to hold the said bracket and side rail against relative angular movement in a vertical plane, said devices, as herein shown, comprising a laterally disposed pin on one of the said parts interfitting with a vertically disposed slot 30 in the other of said parts.

35 Referring to the form of the invention illustrated in Figs. 1 to 7 inclusive, Fig. 1 shows a sheet-metal blank cut to provide outer and inner side walls 1 and 2 that are bent downwardly on the dotted lines *a*, *b*, 40 a top or shelf plate 3, and a pair of rear wall members 4 and 5 that are bent inwardly on the dotted lines *c*, *d* into overlapped relation and are rigidly attached to the bed post 6 by bolts or studs 7. From the inner side 45 plate 2 there is cut and bent upwardly on the dotted line "e" a horizontal attachment lug 8, and from the same side plate there is cut and bent outwardly on the dotted line "f" a vertical attachment lug 9. To the lugs 8 and 9 are riveted the horizontal and vertical 50 limbs of an angle end rail 10 of the bed frame. This end rail is provided with a longitudinal slot 11 in its horizontal limb (Figs. 3 and 6) for a purpose hereinafter 55 shown. In the top or shelf plate 3 there is also cut a slot 12.

13 designates an angle side rail, the end of which may be reduced in width, as shown in Fig. 5, to fit within the corner bracket. 60 In the horizontal limb of the end of the side rail is cut a slot 14 (Fig. 5) which, when the rail is fully entered in the bracket, registers with the slot 12. Through the registering slots 12 and 14 is passed a keeper lug 15 of 65 the general U-form illustrated in detail in

Fig. 7. The curved lower portion of the lug 15 is preferably tapered from edge to edge, and when the lug is in place, it is engaged by a wedge-shaped key 16, best shown in Fig. 3, said key being provided with a 70 stem or shank 17 extending beneath the horizontal limb of the end rail 10 and slidably secured to the latter by a stud 18 mounted therein and slidable through the slot 11 when the wedge 16 is forced inwardly or drawn 75 outwardly by a thumb piece 19 on the outer end of its stem. The side limbs of the keeper lug 15 have heads 15' which rest on the top plate 3 of the bracket, straddling the slot 12. By means of this device the side rail is 80 strongly and securely locked to the top plate of the bracket in such a manner as to transmit all vertical strain to the latter and, through the fastening studs 7, to the bed 85 post.

In the outer side wall 1 of the bracket is secured a headed stud 20. This stud, when the side rail is fully entered into the bracket, is engaged with the bottom of a vertical notch 21, cut in the end of the vertical limb 90 of the side rail 13. The notch 21 is formed with a horizontal entrance way or slot 22. As the rail is passed through the bracket, the stud 20 passes through the entrance slot 22, and as the rail is then raised to bring its 95 top surface against the top or shelf plate of the bracket, the stud 20 reaches its final position at the bottom of the notch 21, and, of course, after the locking key 16 has been applied, the stud 20 is locked in the bottom 100 of the notch 21 against any possibility of displacement except by first withdrawing the key 16.

The stud 20 cooperating with the notch 21 effectively prevents any angular or tilting 105 movement of the post and bracket relatively to the side rail in a vertical plane, for the reason that such angular or tilting movement, under the strains tending to cause the same, involves a relative upward movement of the side rail and downward movement of the bracket, and the engagement of the stud with the bottom of the notch makes this impossible when the locking key 16 110 is in place.

In the form of the invention illustrated in Figs. 8 to 12 inclusive, the same form and structure of box bracket as that already described is employed. Also the same attaching means for the end rail, and the same lug and key means for locking the side rail to the top plate of the bracket. These parts are therefore identified by the same reference numerals heretofore employed to designate them, and need not be again described. 115

Referring first to Fig. 12, to each end of the side rail 13 is strongly riveted an extension member designated as an entirety by 30. This extension member is of general 120 rectangular form comprising an outer side 125

wall 31, a top wall 32, a bottom wall 33 and a pair of inwardly extending lugs or ears 34 and 35 integral with the inner edges of the top and bottom walls 32 and 33. The top and bottom walls 32 and 33 are formed with key slots 36 and 37 corresponding functionally with the key slot 14 of Fig. 5, and the outer side wall 31 is provided with opposed vertical notches 38 and 39 and a common entrance way or slot 40 that corresponds functionally with the notch 21 and entrance slot 22, of Fig. 5. Between the lugs 34 and 35 is an entrance way or slot 41 that corresponds with the slot 40 on the other side. This structure is designed to enable the side rail to be engaged with the corner bracket in either the upright or inverted position. By upright position is understood the position illustrated in Figs. 8, 9 and 10 wherein the horizontal flange of the side rail is uppermost and adapted to support a bed spring frame; while by inverted position is understood the position illustrated in Fig. 11 wherein the horizontal limb of the side rail is lowermost and is adapted to support cross slats. Secured in and extending crosswise between the outer and inner side walls of the bracket is a stud or pin 42. As the side rail extension is moved endwise into the bracket, the stud 42 passes through the entrance slots 40 and 41, and as the rail is then raised and locked to the top plate of the bracket, the stud comes to rest in the bottom of one of the notches 38, 39 and directly behind the corresponding lug 35, 34, according to whether the rail is placed in upright or inverted position. This construction not only permits the application of the rail in either upright or inverted position, but by reason of the double engagement of the rail extension with both side walls of the bracket through the pin or stud 42 it affords great strength and resistance to angular bending strains hereinbefore referred to.

Figs. 13 to 17 inclusive illustrate further modifications in both the top and side locking devices which may be employed within the scope of the invention. Referring to the top locking device, instead of slotting the top plate of the bracket for the passage of the keeper lug, the same is provided with a pair of holes 50, and the upper ends of the limbs of the keeper lug 15^a (Fig. 17) are provided with tenons 51 which pass upwardly through the holes 50 and at their upper ends are riveted over the top plate of the bracket, as indicated at 52. By this construction the keeper lug is permanently secured to the bracket plate, and the latter is not weakened by the cutting of a slot therein sufficiently large to admit the passage of the keeper lug.

The side locking devices embody the same principle as the corresponding devices

already described, but in this case the bracket extension designated as an entirety by 53 (Fig. 16) has the same top, bottom and outer side walls as the bracket extension shown in Fig. 12 and is also formed with an inner side wall 54 which, however, does not extend to the outer end of the structure in order to leave an opening for the passage of the main locking key 16. The side walls of the bracket are formed with vertical notches 55, and the side walls of the bracket extension 53 carry headed studs 56 that engage with the notches 55, said studs 56 being located at mid-height of the bracket extension 53. The side rail extension is engaged with the bracket by entering it at a level at which the studs 56 clear the lower edges of the side plates in advance of the notches 55, and then raising it to permanent position in which the studs lie in the upper or closed ends of the notches. This, it will be observed, is a simple reversal of the stud and notch arrangement previously described, but secures the same result of resisting relative angular displacement in a vertical plane of the side rail and bracket, since the tendency of the bracket to swing downwardly relatively to the studs, or of the studs to swing upwardly relatively to the bracket, is opposed by the engagement of the studs with the closed ends of the notches. This structure, like that shown in Figs. 8 to 10 inclusive, allows the side rail to be positioned in either upright or inverted form. In this construction I have shown the bracket applied to a corner post 6' of square form in cross-section, but, of course, the form of the post is immaterial since the back wall of the bracket will be shaped to conform to the surface formation of the post to which it is attached.

Figs. 18 to 21, inclusive, illustrate a modification of the side locking devices of Figs. 13 to 16 inclusive. In this embodiment of the invention, the outer and inner side walls of the bracket are equipped, slightly below the top plate with studs 60 and 61. The side rail extension 62 (Fig. 21) is formed with four transverse corner slots, namely, upper and lower slots 63 and 64 on its outer side and similar upper and lower slots 65 and 66 on its inner side. In this construction the side rail extension is engaged with the bracket by entering the same at a sufficiently low level to enable the top wall of the bracket extension to slide beneath the studs 60, 61 until the latter register with the slots 63, 65 or 66, 64 (accordingly as the rail is applied in upright or inverted position) and then raising the rail and thereby carrying the studs 60, 61 to their seats in the bottoms of the side wall portions of the notches. Here again, any tendency to relative angular movement of

the side rail and bracket in a vertical plane is strongly opposed by the engagement of the studs with the bottoms of the notches.

Since the side rail attachment members 5 herein shown are rigidly and permanently fastened to the side rail proper and constitute in effect end portions of the latter, it is to be understood that wherever the ends or end portions of the side rails are referred to in this specification or in the 10 claims, I have meant to designate either integral end portions, or attached end portions, of the side rails. The term side rail as used herein is intended to include either 15 the side rail of a bed frame or the side rail of a bed-spring frame.

It is believed that the foregoing description in connection with the drawings will 20 make clear to those skilled in the art the novel structural features of the present invention and the principle underlying the same. Manifestly the forms shown and described by no means exhaust the structural variations and modifications that are 25 possible within the principle of the invention, but they are believed to be sufficient to make clear the structural and functional advantages which inhere therein. Hence, I do not limit the invention to the specific 30 forms, arrangements and proportions shown in the drawings, but reserve all such variations and modifications as fall within the spirit and purview of the appended claims.

I claim:

35 1. In a corner lock for bedsteads, the combination with a box bracket and a side rail having an end portion adapted to engage a locking member on said bracket under a vertical sliding movement, of means 40 for locking said end portion to a horizontal plate of said bracket, and interfitting means on a side wall of said bracket and a vertical limb of said end portion, brought into engagement under said vertical sliding movement co-operating with said first-named 45 locking means to oppose relative angular movement in a vertical plane of said bracket and side rail.

2. In a corner lock for bedsteads, the 50 combination with a box bracket and a side rail having an end portion adapted to engage within said bracket under an endwise sliding movement, of means for locking said end portion to a horizontal plate of said bracket, and interfitting means on a side wall of said bracket and a vertical limb of 55 said end portion, brought into engagement under a relative vertical movement of said parts serving in co-operation with said first-named locking means to oppose relative angular movement in a vertical plane and also relative horizontal movement of 60 said bracket and side rail.

3. In a corner lock for bedsteads, the 65 combination with a box bracket, and a side

70 rail having an end portion fitting within said bracket, of interlocking means for fastening said end portion to a horizontal member of said bracket, and other means co-operating with said interlocking means to prevent relative angular movement in a vertical plane of said bracket and side rail, said other means comprising a vertical notch in one of said parts and a cooperating member on the other engaged with said 75 notch.

4. In a corner lock for bedsteads, the combination with a box bracket, and a side rail having an end portion fitting within 80 said bracket, of means for locking said end portion to the top plate of said bracket, and other means co-operating with said locking means to prevent relative angular movement in a vertical plane and also relative horizontal movement of said bracket 85 and side rail, said other means comprising an inwardly projecting pin on a side wall of said bracket, and a vertical notch in the vertical limb of said end portion engaged with said pin.

5. In a corner lock for bedsteads, the combination of a hollow bracket, means, including a lug, and a key engaging the said lug, for locking a horizontally disposed member of a side rail to a horizontally disposed plate of the said bracket, and co-operating means on a side wall of the said bracket and a vertical member of the said side rail opposing relative angular movement in a vertical plane of the said bracket 95 and side rail.

6. In a corner lock for bedsteads, the combination of a hollow bracket, means, including a lug, and a key engaging the said lug, for locking a horizontally disposed plate of the said bracket, and co-operating means on a side wall of the said bracket and a vertical member of the said side rail, brought into engagement by a 100 relative vertical movement of the said parts, for opposing relative angular movement in a vertical plane of said bracket and side rail.

7. In a corner lock for bedsteads, the combination with a box bracket, of a side 115 rail having a horizontal limb thereof within said bracket and lying against a horizontal plate of the latter, a keeper lug carried by one of said last named parts and passed through the other, an end rail attached to 120 the inner side of said bracket, and a locking key slidably mounted on the said end rail and engaging with said lug.

8. In a corner lock for bedsteads, the combination with a bracket, and a side rail having an end portion fitting within said bracket, of interlocking means for fastening said end portion to a horizontal member of 125 said bracket in either the upright or inverted position of said side rail, and coop-

- erating means on a side wall of said bracket and a vertical limb of said end portion, interfitting with each other in either the upright or inverted position of said side rail, 5 and cooperating with said first-named means in opposing relative angular movement in a vertical plane of said bracket and side rail.
9. In a corner lock for bedsteads, the combination with a box bracket, and a side rail 10 having an end portion fitting within said bracket of interlocking means for fastening said end portion to a horizontal member of said bracket in either upright or inverted position of said side rail, and cooperating 15 means on a side wall of said bracket and a vertical limb of said end portion, interfitting with each other in either the upright or inverted position of said side rail and cooperating 20 with said first-named means in opposing both relative angular movement in a vertical plane and horizontal sliding movement of said bracket and side rail.
10. In a corner lock for bedsteads, the combination of a bracket comprising a back 25 wall adapted to fit the bed post, outer and inner side plates, and a horizontally disposed plate between the latter, a side rail end portion having outer and inner vertically disposed plates fitting between the said 30 outer and inner side plates of the bracket and a horizontally disposed plate integral with said vertically disposed plates a rail locking element on each side wall of the bracket interlocking with a co-operating rail 35 locking element on each vertical member of the said side rail end portion, and means for locking the said horizontally disposed plate of the bracket to said horizontally disposed plate of the side rail end portion, said means 40 including a projecting rail locking member on one of said plates engaged with an aperture in the other of said plates.
11. In a corner lock for bedsteads, the combination of a bracket comprising a back 45 plate adapted to fit the bed post, outer and inner side plates, and a horizontally disposed plate between the said side plates, a side rail end portion including outer and inner vertical plates fitting between the said 50 outer and inner side plates of the bracket, means comprising a pin mounted on and extending between the said outer and inner side plates of the bracket interlocking with a slot in the said outer and inner vertical plates of the said side rail end portion for locking said side and vertical plates respectively to one another, and means for locking the said horizontally disposed plate of the bracket to the said side rail end portion, 55 said means including a rail locking member projecting from one of said parts engaged with an aperture in the other of said parts.
12. In a corner lock for bedsteads, the combination of a box bracket, a side rail end 60 portion including outer and inner vertical plates adapted to fit between the outer and inner side walls of the bracket under a relative endwise movement of the said bracket and side rail, co-operating interlocking means on the said outer and inner vertical 70 plates and side walls brought into engagement by a relative vertical movement of the said vertical plates and side walls, and means, including co-operating elements on the said side rail end portion and a horizontally disposed portion of the bracket, brought into interfitting relation under a relative vertical movement, for locking the said portions to one another.
13. In a corner lock for bedsteads, the combination of a box bracket, a side rail end portion including outer and inner vertical plates adapted to fit between the outer and inner side walls of the said bracket, means on the said outer and inner vertical plates 80 of the side rail end portion interlocking with a co-operating rail locking element on the outer and inner side walls of the bracket under a relative vertical movement for locking said vertical plates and side walls respectively to one another in either the upright or inverted position of the side rail, and means, including interengaging elements on the side rail end portion and a horizontally disposed portion of the said 85 bracket for locking said portions to one another in either the upright or inverted position of the side rail.
14. In a corner lock for bedsteads, the combination of a box bracket, a side rail end portion, including spaced vertical members and upper and lower horizontally disposed plates, disposed between the outer and inner side walls of the said bracket, means on the vertical members of the said rail end portion 90 interlocking with co-operating means on the side walls of the bracket under a relative vertical movement for locking said vertical members and side walls to one another in either the upright or inverted position of the side rail, and means for locking a horizontally disposed plate of the said side rail end portion to a horizontally disposed portion of the said bracket in either the upright or inverted position of the said side rail, said 95 means including a rail locking member on one of said parts engaged with an aperture in the other of said parts.
15. In a corner lock for bedsteads, the combination of a box bracket, a side rail 100 having an end portion including outer and inner vertical limbs adapted to engage within and between the outer and inner side walls of the said bracket under a relative endwise movement of the said bracket and side rail, co-operating means on the said outer and inner vertical limbs of the side rail end portion and the outer and inner side walls of the bracket, brought into interfitting relation by a relative vertical move- 105
- 110
- 115
- 120
- 125
- 130

ment of the said limbs and walls, for locking said outer and inner limbs and walls respectively to one another in either the upright or inverted position of the said side rail, and means on said side rail end portion interengaging with means on a horizontally disposed portion of the bracket for locking said portions, in either the upright or inverted position of the said side rail, against relative horizontal movement.

16. In a corner lock for bedsteads, the combination of a box bracket, a side rail having an end portion comprising outer and inner vertical plates fitting between the outer and inner side walls of the bracket, means comprising oppositely facing slots in the said outer and inner vertical plates of the side rail end portion interlocking with a rail locking member located on and between the said outer and inner side walls of the bracket, for locking the said vertical plates and side walls respectively to one another in either the upright or inverted position of the said side rail, and means for locking said side rail end portion to a horizontally disposed portion of the bracket in either the upright or inverted position of the said side rail, said means including a projecting rail locking element on one of said portions interfitting with a co-operating rail-locking element on the other of said portions.

17. In a corner lock for bedsteads, the combination of a box-like bracket, a side rail end portion having a vertical limb and vertically spaced horizontal limbs and hav-

ing its vertical limb disposed within the said bracket, means for locking a side wall of the said bracket to the said vertical limb of the side rail end portion in either the upright or inverted position of the said side rail, said means comprising a fixed laterally projecting rail locking element on one of the said parts entering a rail locking slot in the other of said parts, and means for locking one of the said vertically spaced horizontal limbs of the side rail end portion to the said bracket in either the upright or inverted position of the said side rail, said means including a vertically projecting rail locking element on one of said parts embraced by a co-operating rail locking element on the other of said parts.

18. In a corner lock for bedsteads, the combination with a box-like bracket having a side plate carrying a pin, of a side rail having an end portion fitting within said bracket, means on said rail end portion for removably locking a vertical member of said end portion to the side plate of said bracket in either the upright or inverted position of the side rail, said means comprising reversely facing slots in the said vertical member adapted to engage with said pin, and coacting auxiliary interlocking means on said bracket and side rail end portion co-operating with said first-named locking means to hold the said bracket and side rail against relative angular movement in a vertical plane.

HENRY RICHARDSON.
